CLAIM

The ornamental design for a ball holding device, as shown and described.

DESCRIPTION

FIG. 1 is a top perspective view of a ball holding device showing our new design;

FIG. 2 is a bottom perspective view thereof;

FIG. 3 is a top plan view thereof;

FIG. 4 is a bottom plan view thereof;

FIG. 5 is a side elevational view thereof taken along line 5—5 of FIG. 3;

FIG. 6 is a side elevational view thereof taken along line 6—6 of FIG. 3;

FIG. 7 is a side elevational view thereof taken along line 7—7 of FIG. 3;

FIG. 8 is a side elevational view thereof taken along line 8—8 of FIG. 3; and,

FIG. 9 is a side elevational view thereof showing an environment in broken lines.

The broken lines are directed to environment and are for illustrative purposes only; the broken lines form no part of the claimed design.
